UNITED STATES PATENT OFFICE.

JAMES GILBERT AND WILLIAM E. PERKINS, OF EAGLE, IDAHO; SAID PERKINS
ASSIGNOR OF ALL HIS RIGHT TO WILBER J. SELBY, OF EAGLE, IDAHO.

ROTARY SIGN-EXHIBITOR.

1,369,170.

Specification of Letters Patent. Patented Feb. 22, 1921.

Application filed June 21, 1920. Serial No. 390,479.

To all whom it may concern:

Be it known that we, JAMES GILBERT and WILLIAM E. PERKINS, citizens of the United States, residing at Eagle, in the county of Ada and State of Idaho, have invented certain new and useful Improvements in Rotary Sign-Exhibitors, of which the following is a specification, reference being had to the accompanying drawings.

10 This invention relates to rotary sign exhibitors.

An important object of the invention is to combine with a rotary exhibitor embodying a plurality of signs, some individual receptacle, such as mail boxes, which when being positioned for the withdrawal of their contents by the proprietor thereof, cause rotation of the sign to bring previously undisclosed portions thereof into view.

20 Other objects and advantages of the invention will become apparent through the course of the following description.

In the accompanying drawings, wherein for the purpose of illustration is shown a preferred embodiment of our invention and wherein like reference characters designate like parts throughout:

25 Figure 1 is a perspective view of our device, and Fig. 2 is a transverse sectional view taken therethrough.

In the construction of our invention we preferably employ a base 10 formed of stone, concrete, or the like, provided in the upper surface thereof with a vertical bore receiving an oil chamber 11. The upper end of the bore is counterbored to form a shoulder 12 which receives the lower face of a thrust collar 13 carried by a vertical shaft 14 which has its lower end disposed within the oil well 11.

40 The shaft 14 is provided above the upper surface of the base 10 with radial arms 15, each of which has secured thereto a mail box 16 or some similar individual receptacle. Between each pair of arms at the extremities thereof is mounted a sign 17 held in position by the frame 18 secured to the arms and to the sign 17 by means of screws 18' or the like.

45 It will be noted that the arms 15 incline downwardly toward their outer ends at a slight angle. A covering 19 is provided extending intermediate the arms in the shaft 14 into proximity to the rear faces of the signs 17, affording between their outer edges

and the sign, a small space. It will be seen that the covering 19 is arranged in the same declining angle as the arms 15 and that, accordingly, rain water will not collect upon this covering but will be deflected beyond 60 the upper surface of the base 10, thus preventing the collection of water upon the upper surface of the base and seepage through the thrust bearing 13 into the oil chamber 11.

65 The upper end of the shaft 14 extends upwardly beyond the radial arms 15 and is preferably provided upon its extremity with an enlargement 14' which may be provided with advertising matter.

70 It will be seen that if our improved sign is arranged at the side of the road, the proprietors of the mail boxes carried thereby, will rotate the sign in order to bring their mail boxes into position for opening, and 75 will accordingly rotate the sign bringing fresh sections thereof, new signs 17, and new portions of the enlargements 14', into view from the road.

75 It will, of course, be understood that the 80 illustration and description accompanying are merely illustrative and that our invention is not limited to the specific construction hereinbefore set forth, but may be so changed without in any manner departing 85 from the spirit of the invention or the scope of the subjoined claims.

Having now described our invention, what we claim is:

1. In a rotary sign exhibitor, a base 90 adapted to be arranged adjacent a right of way, a vertical shaft rotatably mounted thereon and embodying a plurality of approximately horizontally disposed radial arms, individual receptacles carried by each 95 of said arms and supporting frames secured to the outer ends of said arms and adapted to receive a sign whereby rotation of the device to place the individual receptacles in position for removal of their contents exposed fresh exhibitory matter to view from the right of way.

2. In a rotary sign exhibitor, a base, a vertical shaft rotatably mounted thereon and embodying a plurality of radial arms, 105 said arms inclining downwardly toward the outer ends thereof, individual receptacles supported by said arms, exhibitory signs secured to the ends of said arms, and a covering extending intermediate said arms and 110

terminating short of the rear face of said signs.

3. In a rotary sign exhibitor, a base, provided in its upper face with a vertical bore, 5 an oil chamber mounted within said bore, said bore being provided with a counterbore forming a shoulder, a shaft provided adjacent the lower end thereof with a thrust collar positioned within said bore and engaging said shoulder, the lower end of said shaft being disposed within said oil well, a

plurality of radial arms carried by said shaft, individual receptacles carried by said arms, frames secured intermediate the outer ends of said arms and adapted to receive 15 signs, and a cover carried by said arms and extending entirely over the upper surface of said base.

In testimony whereof we hereunto affix our signatures.

JAMES GILBERT.

WILLIAM E. PERKINS.
